UNITED STATES PATENT OFFICE.

WALES ALDRICH, OF MIAMISBURG, OHIO, ASSIGNOR TO HOOVER & GAMBLE,
OF SAME PLACE.

MOWING-MACHINE.

SPECIFICATION forming part of Letters Patent No. 388,807, dated September 4, 1888.

Application filed September 17, 1884. Serial No. 143,268. (No model.)

To all whom it may concern:

Be it known that I, WALES ALDRICH, a citizen of the United States, residing at Miamisburg, in the county of Montgomery and State 5 of Ohio, have invented certain new and useful Improvements in Mowing-Machines, of which the following is a full, clear, and exact description, reference being had to the accompanying drawings, forming a part of this specification.

10 My invention relates to an improvement in that class of mowing-machines known as "front-cut" mowers, and has for its object the general improvement in the construction of the machine, whereby simplicity, efficiency, 15 and strength are obtained.

The novelty consists in the construction and combination of the elements employed, all as will be herewith set forth and specifically claimed.

20 In the accompanying drawings, Figure 1, Sheet 1, is a side elevation of my improved machine. Fig. 2, Sheet 1, is an enlarged transverse sectional view of the pole or tongue, showing the application of the sliding double-tree. Fig. 3, Sheet 2, is a plan view of the machine. Fig. 4, Sheet 3, is a detailed plan view, partly in section, of the tilting-bar. Fig. 25 5, Sheet 3, is an enlarged detailed view, partly in section, of the inner shoe and the gag-lever for raising and lowering the finger-bar. Fig. 6, Sheet 3, is an enlarged detailed view, partly in section, showing the coupling of the yoke-extension to the main frame. Fig. 7, Sheet 3, is an enlarged detailed view of the 30 pitman-head. Fig. 8, Sheet 3, is a corresponding view in central section.

The same letters of reference are used to indicate corresponding parts in all the figures.

A is the usual or any suitable frame-work, 40 in which is journaled the axle B, upon the outer ends of which the driving and supporting wheels C C' are secured by the usual ratchet-and-pawl connections.

D is the pole or tongue, suitably secured to 45 the main frame, as is also the driver's seat E.

F is the usual or any suitable finger-bar, and G the knife, the former of which is secured to the customary inner shoe, H, and outer di- 50 vider-shoe, I. The usual driving-gear is contained in the box J of the main frame and com-

municates motion to the knife G through the pitman K.

The inner wheel, C', is of slightly greater diameter than the outer wheel, C. The wheels act on the principle of the lever, the power 55 being applied at the axle and the ground upon which the wheels rest being the fulcrum. The lever of the inner wheel, C', is longer than that of the outer wheel, C. The power being applied near the center of the axle, the draft on 60 each wheel is the same, and, the leverage of the inner wheel being the greater, it will be turned more easily than the outer one, and will have a tendency to move along the ground faster than the outer one. The cutting apparatus being on the side having the larger wheel, its resistance overcomes the tendency 65 of this wheel to move its side of the machine faster than the other, and the larger wheel may be made of such size with reference to the 70 smaller that its tendency to move its side of the machine faster than the latter moves its, exactly counterbalances the resistance of the cutting apparatus, and the machine will move forward in a straight line without any side 75 draft.

The finger-bar is rigidly secured to the inner shoe, H, which shoe is hinged to the yoke L, as shown, so as to permit the finger-bar to follow the inequalities of the ground and to be 80 turned upon the yoke in transporting the machine from place to place when not in use, and said yoke has a rear socket-piece, a, in which, as seen in Fig. 4, is pivoted so as to have slight lateral play a rearwardly-extending 85 thrust-bar, M, whose rear end, enlarged, as shown at b, fits into the open T-slotted segment N, which is secured to the main frame, as shown, the purpose of this lateral play being to prevent the thrust-bar from binding in the 90 slotted segment. The yoke is further supported by a coupling-bar, O, whose outer end is connected by the swiveled joint shown in Fig. 6, where a spindle, a', extending from the bar O, passes through a countersunk or tapering aperture, b', in the main frame A, and has slipped upon its rear end a hemispherical washer, c', fitting into a concavity in the frame, the parts being united by the washer d' and key e', as shown.

This construction unites the coupling-bar O to the forward extension of the main frame, as seen at c, in such manner as to permit the shoe and finger-bar to be tipped fore and aft, or 5 raised bodily up or let down. The tipping of the finger-bar is accomplished by the hand lock-lever P, whose lower curved end is connected by a link, d, to the bar M, as seen in Fig. 1. The fulcrum of lever P being in close 10 proximity to bar M, the inclination of the finger-bar in both directions can be effected in a comparatively small sweep of the lever. To obtain a direct draft and the power of the team directly upon the cutting apparatus, I secure 15 any suitable bracket or casting, R, to the pole or tongue, over which is fitted, so as to be free to slide, a second engaging-casting, S, to which the doubletree T is secured, as seen in Figs. 1 and 2. From this casting S, which forms part 20 of the sliding doubletree, a draft-bar, U, extends down and back, and is hooked at its rear end into either of the adjustment-holes e of an upwardly-extending lug or arm, f, integral with the bar O and at a point close to the 25 yoke L. It will be seen from this construction that the draft-power of the machine is communicated directly through the sliding doubletree to the cutting apparatus, and owing to the leverage on bar O afforded by lug f, the forward tipping of the cutting apparatus is materially assisted by the draft of the team.

V is the finger-bar-lifting hand lock-lever, pivoted to the side of the tongue and having at its lower end a grooved quadrant, W, to the 35 upper end of which is hooked or fastened the top of a chain, g, which extends down and has its lower end connected to the rear end of a gag-lever, Y, pivoted at h to lugs i upon the yoke L, and with its front engaging end passing through a slot in the yoke and bearing upon the upturned end of a piece, j, bolted or otherwise secured to the finger-bar, as seen in Fig. 5.

In operation the first action of lever V is 45 to raise the shoe bodily for a short distance, whereupon the gag-lever comes into play and folds the finger-bar.

As k, Fig. 5, is the pivotal axis of the shoe H, it will be seen from this construction that 50 I not only obtain a powerful leverage to throw up the finger-bar, but at the same time do not have to move the hand-lever V but a comparatively short distance.

By reference to Figs. 7 and 8 the construction of my improved self-oiling pitman-head will be shown. The wrist-pin upon the balance-wheel l has its end formed into a ball, so as to constitute with the end of the pitman a ball-and-socket joint, the socket of which is

formed by the pitman-head, which in this 60 instance is composed of the tubular portion m into which the end of the pitman K is screwed, and which at its opposite end is formed into a hemispherical chamber, n, communicating with the bore o. A detachable piece, p, with its 65 inner side concave, is fitted between upper and lower extensions, r s, of the tube m, as shown, and is held in place by a bolt, x, inserted through a lug, t, and a perforation in the end of a hinged piece, u, pivoted between 70 ears of the extension s at v. A nut, w, serves to unite the parts. In applying this pitman to the wrist-pin it is only necessary to remove the nut w, whereupon the piece u can be swung back to enable the two-part socket to be slipped 75 over the head of the wrist-pin, when the parts are again brought into position and locked by the nut. An essential feature of this construction is the bore o, which forms an oil-chamber, 80 into which the oil is poured at the opening y to fill the same, and which, communicating with the socket of the joint, serves to effectually lubricate the same at every stroke of the pitman.

Having thus fully described my invention, 85 I claim—

1. The combination, with the yoke having a rearwardly-extending socket-piece, of a thrust-bar pivoted at one end in said socket-piece in such manner as to have lateral play, 90 a T-slotted segment, with which the other end of the thrust-bar engages, a hand-lever, and a link connecting the thrust-bar and the lever, substantially as described, and for the purposes specified. 95

2. The combination, with the yoke L, coupling-bar O hinged at one end to the yoke and swiveled at its other end to the forward extension of the main frame, and the lug f, projecting from the coupling-bar near the yoke, 100 of the sliding doubletree T and draft-link U, substantially as described, and for the purpose stated.

3. The pitman-head composed of the tubular portion m, detachable piece p, hinged locking-plate u, and bolt x, the parts constructed and applied in the manner and for the purpose specified. 105

4. The combination, with the coupling-bar O and the main frame perforated and recessed to receive it, of the spindle a', hemispherical washer c', fitting and playing in a corresponding recess in the main frame, washer d', and key e', substantially as described. 110

WALES ALDRICH.
